ATTORNEY

UNITED STATES PATENT OFFICE.

LAKE E. FUGATE, OF SEATTLE, WASHINGTON.

PISTOL-HOLDER.

SPECIFICATION forming part of Letters Patent No. 681,392, dated August 27, 1901.

Application filed February 4, 1901. Serial No. 45,992. (No model.)

To all whom it may concern:

Be it known that I, LAKE E. FUGATE, a citizen of the United States, residing at Seattle, in the county of King and State of Washington, have invented certain new and useful Improvements in Pistol-Holders, of which the following is a specification, reference being had therein to the accompanying drawings.

This invention relates to pistols; and, 10 broadly speaking, it consists in a projecting stud permanently secured to the pistol-stock and a hanger formed from a plate of metal which is adapted to be hooked upon a person's clothing, as at the waistband of the 15 trousers or upon a belt, and having a slot for engaging with the said stud, by which the pistol is hung.

My invention is particularly intended for use with street-clothes, where the pistol is to 20 be carried beneath the coat, close to the person's body, and readily disengaged from the hanger, as hereinafter more fully set forth.

Referring to the accompanying drawings, Figure 1 is a front view of the hanger with a 25 pistol, which is indicated in dotted lines, attached thereto. Fig. 2 is an end view of the same with the pistol-supporting stud in engagement. Figs. 3 and 4 are perspective views of the hanger from the back and front, 30 respectively. Fig. 5 is a longitudinal view of the supporting-stud.

In the said drawings, 1 represents a stud, which is an extension of the pistol hammer-buttpin 2.

35 3 is the hanger attachment, formed simply from a plate of metal folded twice, once inwardly to form a hook 4 to embrace the trousers-band or other part of the clothing to which it is hung and preferably having a 40 vertical slot 5 formed in the rear leaf to engage over a button or suspender-strap to prevent the dislodgement of the hanger. The other fold 6 is bent outwardly and having a horizontal or approximately horizontal slot 45 7 from the forward edge of the leaf and ter-

minating in a saddle or hook-shaped end 10, in which the stud 1 is lodged when the pistol is carried by the hanger. The neck of the stud 1, between the collars 8 8' formed thereon, is admitted to the saddle 10, and the said 50 collars bear against the surfaces of the plate adjacent to the slot to retain the said stud perpendicular to the face thereof.

9 is a depression in the middle leaf 11 directly in the rear of the slot 7 to provide a lead 55 to guide the collar 8' into the aforesaid slot 7.

Having now described my invention, what I claim as new, and desire to secure by Letters Patent, is—

1. In a device of the character described, 60 in combination with a pistol having a stud projecting from the stock thereof, of a hanger for attaching the pistol to a person's clothing consisting of a plate of metal folded twice, once inwardly to form a suspension-hook, and once 65 outwardly with a slot therein having a hook-shaped end to receive and support the said stud, substantially as and for the purposes described.

2. In a holder of the character described, 70 in combination with a pistol, of suspending devices, which devices comprise a stud extension to the pistol hammer-buttpin formed with two collars thereon, and a hanger for attaching the pistol to a person's clothing consisting 75 of a plate of metal folded to form a suspension-hook, another folded at right angles to the aforementioned fold with a slot having a hook-shaped end for the reception of the said stud, and a depression in the main portion of the plate to the rear of and adjacent to the mouth of the said slot, substantially 80 as and for the purposes described.

In testimony whereof I affix my signature in presence of two witnesses.

LAKE E. FUGATE.
